UNITED STATES PATENT OFFICE

142,066

DESIGN FOR A RESISTANCE WELDER

Ulysses S. Dunn, Aurora, Ill.

Application August 14, 1944, Serial No. 114,878

Term of patent 14 years

(Cl. D26—5)

To all whom it may concern:

Be it known that I, Ulysses S. Dunn, a citizen of the United States, residing at Aurora, in the county of Kane and State of Illinois, have invented a new, original, and ornamental Design for Resistance Welder, of which the following is a specification, reference being had to the accompanying drawing, forming a part thereof.

In the drawing:

The figure is a perspective view of the resistance welder, showing my new design.

The rear of the welder is plain and the side not shown is substantially the same in appearance as the side illustrated.

I claim:

The ornamental design for a resistance welder, substantially as shown and described.

ULYSSES S. DUNN.
